UNITED STATES PATENT OFFICE.

ANDREW WIRSING, OF MILWAUKEE, WISCONSIN.

HOISTING-BUCKET CARRIER.

SPECIFICATION forming part of Letters Patent No. 705,806, dated July 29, 1902.

Application filed October 25, 1901. Serial No. 79,933. (No model.)

To all whom it may concern:

Be it known that I, ANDREW WIRSING, a citizen of the United States, and a resident of Milwaukee, in the county of Milwaukee and State of Wisconsin, have invented certain new and useful Improvements in Hoisting-Bucket Carriers; and I do hereby declare that the following is a full, clear, and exact description thereof.

My invention has especial reference to the organization of hoisting-bucket carriers, to provide for automatic latching and unlatching of the same at hoisting-stations of their tracks, and also to provide for automatic catch and release of hoisted buckets with respect to said carriers, said invention consisting in certain peculiarities of construction and combination of parts hereinafter particularly set forth with reference to the accompanying drawings and subsequently claimed.

Figure 1 of the drawings represents a vertical longitudinal section view of one of my improved hoisting-bucket carriers in conjunction with its track and a portion of a bucket; Fig. 2, a plan view of the carrier and track, buffer-blocks on the track being in horizontal section; and Fig. 3, a vertical transverse section view indicated by lines 33 in first figure.

Referring by letter to the drawings, A indicates each of the rails of an overhead track, and B a buffer-block on each rail. Arranged on the track are wheels C of a carrier of ordinary construction, except as to details hereinafter specified, said carrier having sheaves D E therewith on which to train suspending and draft cables F G, pertaining to a hoisting-bucket, preferably of the separable variety set forth in my Patent No. 667,476, of February 5, 1901.

The side plates H of the carrier are each provided with an inclined lower recess b, and a curved-edge lower projecting portion c of each plate constitutes a guide leading to the recess. Spaced apart by a sleeve d on a pivot e, connecting the side plates H of the carrier, are bell-cranks I, the normally lower arms of which are the heaviest and provided with stops f g, that limit independent play of dogs J, spaced apart by a sleeve h on a pivot i, connecting said bell-cranks, these dogs being normally crosswise of the aforesaid recesses in said plates. Collars d' are shown on pivot

e between the bell-cranks and side plates of the carrier, and collars h' are shown on pivot i between said bell-cranks and the dogs in connection therewith. The ends of curved branches K' of a latch K in pivotal connection with plates H are also crosswise of the recess b at an elevation greater than that of the aforesaid dogs, and the weighted end of a yoke L, pivoted between said plates, opposes the bell-cranks I to normally hold the same in the position shown by full lines in Fig. 1, a support j being provided for said end of the yoke. Latch K engages with a rod M, in connection with angle-plates N, fast to the buffer-blocks B of the carrier-track, and another rod P, in connection with said angle-plates, is arranged to oppose a curved shank L' of the yoke L, this yoke being automatically lifted by movement of its shank under the opposing rod.

In practice the carrier is held at the hoisting-station of the track by engagement of latch K with rod M, and the transverse pin Q of an ascending bucket is guided into recesses b of plates H by the depending plate projections c to pass the yielding dogs J and eventually operate against the branches K' of said latch to tilt the latter free of said rod. For the time being the dogs J prevent disengagement of the bucket-pin Q from the plate-recesses of the carrier, and said carrier being unlatched it is free to travel with the bucket to the dumping-station of the track, said bucket being held in suspended connection with the aforesaid carrier when the dumping operation takes place, notwithstanding that there is slack of the suspending-cable in connection with said pin. On return of the carrier and bucket to the hoisting-station of the track the latch K passes under rod M to be caught by the same, and said carrier runs back far enough to force yoke-shank L' under rod P', whereby the weighted end of yoke L is lifted, and, owing to the weight of said bucket, the bell-cranks I, with the dogs J, are swung to the position shown by dotted lines in Fig. 1, so that bucket-pin Q may automatically clear the recesses b in the side plates H of said carrier. Release of the bucket having been automatically effected the carrier moves ahead a limited distance to have its latch K catch against the rod M, the

bell-cranks I, dogs J, and yoke L being in the meantime automatically restored to normal position.

Although the branches K' of latch K are 5 herein shown between the carrier-plates, it is practical and at times desirable to have them outside of said plates.

Having thus described my invention, what I claim as new, and desire to secure by Letters 10 Patent, is—

1. A hoisting-bucket carrier having its side plates provided with recesses arranged to be engaged by a bucket-pin, bell-cranks intermediate of the plates, dogs having limited 15 pivotal play on arms of the bell-cranks to be normally crosswise of the plate-recesses, a latch in pivotal connection with the carrier having branches that are also crosswise of said recesses above said dogs, and a pivotal 20 yoke with said carrier in opposition to said bell-cranks, the latch being engageable with a stationary catch adjacent to a stationary striker in the path of a curved shank of the yoke.
- 25 2. A hoisting-bucket carrier having its side plates provided with recesses arranged to be engaged by a bucket-pin, guides to the recesses in the form of curved lower projections of the plates, bell-cranks intermediate of said plates, 30 dogs having limited pivotal play on arms of the bell-cranks to be normally crosswise of the plate-recesses, a latch in pivotal connection

with the carrier having branches that are also crosswise of the plate-recesses above said dogs, and a pivotal yoke with said carrier in 35 opposition to said bell-cranks, the latch being engageable with a stationary catch adjacent to a stationary striker in the path of a curved shank of the tilt-yoke.

3. A hoisting-bucket-carrier track having 40 buffer-blocks, stationary rods transversely of the track, the carrier having its side plates provided with recesses arranged to be engaged by a bucket-pin, bell-cranks intermediate of the plates, dogs having limited pivotal 45 play on arms of the bell-cranks to be normally crosswise of the plate-recesses, a latch in pivotal connection with said carrier having branches that are also crosswise of said recesses above said dogs, and a pivotal yoke 50 with the aforesaid carrier in opposition to said bell-cranks, the latch being engageable with one of the aforesaid rods and the other rod arranged in the path of a curved shank of the yoke.

In testimony that I claim the foregoing I have hereunto set my hand, at Milwaukee, in the county of Milwaukee and State of Wisconsin, in the presence of two witnesses.

ANDREW WIRSING.
